Primary Examiner — Steven J Czyz(74) Attorney, Agent, or Firm — Daniel M. Cohn;
 Howard M. Cohn(57) CLAIM

The ornamental design for a TV stand with electric fireplace, as shown and described.

DESCRIPTION

FIG. 1 is a front elevational view of a TV stand with electric fireplace showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is a perspective view of the TV stand with electric fireplace where the TV stand with electric fireplace is in a configuration of use.

The broken lines in FIG. 9 are directed to environment and form no part of the claimed design.

1 Claim, 9 Drawing Sheets(56)
